CLAIM

The ornamental design for a retail store facade, as shown and described.

DESCRIPTION

FIG. 1 is a general perspective view of the retail store facade embodying the present invention;

FIG. 2 is a front elevation of the retail store facade shown in FIG. 1; and,

FIG. 3 is a top plan view of the retail store facade shown in FIG. 1.

The rear, bottom and sides of the retail store facade form no part of the claimed design.
